O. D. WARNER, OF BRISTOL, CONNECTICUT, ASSIGNOR TO HIMSELF
AND S. M. SUTLIFF, OF THE SAME PLACE.

Letters Patent No. 86,116, dated January 19, 1869.

IMPROVEMENT IN ALARM-LOCKS.

The Schedule referred to in these Letters Patent and making part of the same.

To all whom it may concern:

Be it known that I, O. D. WARNER, of Bristol, in the county of Hartford, State of Connecticut, have invented a new and improved Alarm-Lock and Latch; and I do hereby declare that the following is a full, clear, and exact description thereof, which will enable others skilled in the art to make and use the same, reference being had to the accompanying drawings, making a part of this specification, in which—

Figure 1 is a front elevation of my invention.

Figure 2 is a side elevation of the bell, attached to the cap or plate.

Figure 3 is a side elevation of the hammer, for sounding the bell.

Similar letters of reference indicate like parts.

My invention consists in placing between or near a latch-bolt and lock-bolt a bell, and a hammer for sounding the same, which hammer is operated by the sliding of either bolt.

A designates the latch-bolt, and B, the lock-bolt, both of which are constructed in any proper manner, and are the same as many in common use.

C designates the bell, attached to the inside of cap or plate D.

E designates a sliding hammer, for sounding the bell C, and having its bearings in studs a a, and placed parallel with the bolts A and B.

At each side of hammer E, I place a stud, b, the top of which is inclined with the highest point from the bell C, and higher than the elevations d d on the top of hammer E. The sides of elevations d d nearest the bell C are at or nearly at right angles with hammer E, while their opposite sides are bevelled or inclined.

To the bolts A and B, I firmly attach, in any proper manner, a spring-bar, F.

When the bolts A or B are extended outward, the spring-bar F rests on the hammer E in front of elevations d d. As the bolts A or B are caused to slide inward, the spring-bar F strikes elevation d, and slides the hammer E with it until the inclined stud b raises the spring-bar F over the elevation d, and the hammer E is released and driven against the bell C by the spring G, while the smaller and weaker spring c will draw the hammer E back sufficiently to give the bell C a clear

tone. As the bolts A or B extend outward again, the spring-bar F slides up the bevelled side of and over elevation d into its former position.

I place, in the inside of the box or frame H of the lock, a sliding wedge, e, which is held in a slot, not shown, and provided with a stud, fitted in said slot, by which it can be operated from the outside of the lock. By sliding the wedge e firmly between the frame H of the lock and the bell C, it will prevent the ringing of the bell C, and its sound, when struck by the hammer E, will be only a click.

This lock and latch is designed for the ordinary mortise-lock and latch, with the bell C inside; but, if desired, the spring-bar F could be set on the side of the bolt, instead of its front, and extend through the lock to the inside side of the door, and the bell C, with the hammer E at e, in proper position under it, placed on the inside side of the door.

The ordinary latch-knob could be labelled, "bell," and attached to this latch, when it would answer for a call-bell, while it will always answer for an alarm, to inform when either the lock or latch is turned.

If desired, the hammer E and bell C can be used for a door-bell, without combining them with a latch or lock, by simply providing any sliding bolt, to attach the spring-bar F, for operating the hammer.

Alarm-bells have before been combined with locks, with a small mechanical movement, so arranged that, by winding and setting, the lock-bolt would, when moved, set the movement in motion, which would oscillate a hammer, and sound the bell; but such or similar combinations I do not claim; but

What I claim as new, and desire to secure by Letters Patent, is—

1. The combination and arrangement of the frame H, sliding wedge e, bell C, and hammer E, operating substantially as and for the purpose described.
2. The combination of bolt A or B, spring-bar F, hammer E, with its elevations d d, inclined stud b, springs G and c, and bell C, substantially as and for the purpose described.

O. D. WARNER.
